UNITED STATES PATENT OFFICE.

PHILIP D. HIBNER, OF SEATTLE, WASHINGTON.

MEANS FOR REGULATING FUEL MIXTURES FOR INTERNAL-COMBUSTION ENGINES.

1,230,404.

Specification of Letters Patent. Patented June 19, 1917.

Application filed July 18, 1916. Serial No. 109,989.

To all whom it may concern:

Be it known that I, PHILIP D. HIBNER, a citizen of the United States, residing at Seattle, in the county of King and State of Washington, have invented certain new and useful Improvements in Means for Regulating Fuel Mixtures for Internal-Combustion Engines, of which the following is a specification.

10 This invention relates to internal combustion engines.

The object of the invention is the provision of improved means for forming a suitably proportioned admixture of hydro-carbon oil and air, and regulating the supply of this combustible to the explosion chamber of the engine for the purpose of controlling the engine speed and its capacity to perform work.

15 The invention consists in the novel construction, arrangement and combination of parts, as will be hereinafter described and claimed.

In the accompanying drawings, Figure 1 is a view in transverse vertical section of apparatus embodying the present invention. Fig. 2 is a view partly in plan and partly in horizontal section of the same. Fig. 3 is a transverse vertical sectional view taken through α - α of Fig. 2 and illustrating the 20 movable elements thereof in different operative positions from which they are represented in Fig. 1.

Referring to said drawings, the numeral 5 designates a casing of tubular form having an oscillatory valve which is constituted of two axially aligned members 6 and 7 spaced to provide a passageway 8 therebetween and extending diametrically of the valve. The valve member 6 consists of a body substantially as shown having parallel side faces 6¹ which fit against faces 7¹ of bifurcations 7² provided on the other member 7. The opposing walls 6³ and 7³ of the respective members are desirably formed in parallel relations with each other and in planes oblique to the axis of the valve.

25 Ports 9 and 9¹ are provided at diametrically opposite sides in the peripheral walls of the casing, and a third port 10 is provided 30 in the casing above the valve. Said ports are

relatively narrow and are disposed helically in the casing so as to register with the respective ends of the way 8 when the valve is suitably rotated.

The oil for the explosive mixture is fed 55 into the valve-way by means of a pipe 11 extending from an oil reservoir 12 to the port 10. The air for such mixture is conducted by a pipe 13 extending from a source of air supply to the port 9, whence it is delivered with the oil through the port 9¹ and the communicating pipe 14 when the valve-way is brought into register with the ports 9 and 9¹. The air and oil composing the explosive agent may be drawn through the delivery pipe 14 by the suction or vacuum generated in the operation of the engine, but preferably the oil is forced from the valve-way and through said delivery pipe by a jet 60 of air supplied under considerable pressure to the pipe 13 whereby the oil is more thoroughly vaporized and combined with the air.

Where compressed air is thus used, a vent hole 15 is provided in the casing intermediate ports 9¹ and 10 for the escape of superfluous air from the valve-way and from 65 which it is led by a pipe 15¹ to the reservoir 12. The quantity of air supplied for each charge is regulated by means of a valve indicated by 16 in the pipe 13 and the amount of oil may be determined by adjusting the relative positions of the valve members 6 and 70 75 to correspondingly vary the size of the way 8.

To these ends, the valve member 7 is secured against end motion and the member 6 80 moved axially in the casing, as by means of a bell-crank lever 17 which is actuated to shift the member through the agency of stem 18. The latter may be connected to the lever by 85 means of a collar 19 engaging in a peripheral groove of the stem and by means of studs, such as 19¹, engaging in slots provided in the forked end 17¹ of the lever.

20 represents a nut carried by the lever arm 17² and engageable with a screw 21 90 which is utilized to influence the lever for adjustably moving the valve part 6.

22 represents a stuffing box provided in the casing and 5¹ to prevent leakage of air about

the stem from the casing chamber 23 through which said stem extends. 24 is a duct for the passage of air from pipe 13 to said chamber.

5 In operation, the valve is oscillated about its axis to present the passageway successively to the aforesaid oil and air pipes for each of the successive cycles in which the engine is supplied with a charge of combustible; for which purpose the valve is provided exteriorly of the casing with an arm 25 carrying a crank-pin 26 extending into a slot 27 provided in the end of a rod 28 which is reciprocated by an eccentric (not shown) 10 driven from the engine shaft or otherwise.

The slot 27 of said rod is made somewhat longer than the diameter of the pin 26 to afford, upon occasion, movement to the rod independently of the motion which is imparted 15 to the crank-arm through the agency of the eccentric rod.

To regulate such relative movements of the rod and crank-arm, I provide in the former adjustable stops in the nature of 25 screws 29 and 29¹ which may be advanced or retracted to lessen or increase the effective space therebetween and likewise regulate the positions at which the pin 26 will be encountered by the respective stops during the reciprocal travel of the same.

The operation of the invention may be explained as follows:

When the valve 6—7 is in the position in which it is represented in Fig. 1, the oil from 35 the reservoir flows into the way 8 until the latter is filled or until the valve is rotated in the direction indicated by the arrow in Fig. 1 to cause such way to be moved out of communication with the port 10. This movement of the valve is effected through the medium of the rod 28 and by regulating the pin-engaging screw 29, it is evident that more or less lost motion may ensue to the rod with affecting the valve to accordingly allow 40 the way thereof to remain in oil-receiving position during the initial portion of the return stroke of the rod.

The continued travel of the rod rotates the valve into the position in which it is represented in Fig. 3 to connect the two ports 9 and 9¹ whereupon the air supplied under pressure by pipe 13 will serve to eject the charge of oil therefrom to escape as a combustible mixture through delivery pipe 14 55 to the explosion chamber of the engine with which my devices are employed.

The way 8 may be caused to remain for a determinable period of time in its Fig. 3 position by adjusting the screw 29¹ (Figs. 1 and 2) so that the rod 28 will have lost motion with respect to the arm 25 during the beginning of the outward stroke of the rod.

As the way 8 passes the vent hole 15 when the valve is being rotated to receive another

charge of oil, communication is established 65 between the way and the air space in the reservoir, resulting in the flow of air, due to its relatively strong pressure, from the way into the reservoir to accelerate the outflow of oil from the same when the way subsequently arrives in position to receive the oil.

By regulating through the offices of lever 17 and stem 18, the axial position of the valve part 6 with respect to the other part 7, the capacity of the way 8 may be selectively 75 varied to increase or decrease the oil charges. The quantity of air supplied through pipe 13 may also be controlled by means of the valve 16.

What I claim, is—

1. In apparatus of the class described, the combination with a closed reservoir for liquid, a valve having a passageway therein, a casing for the valve, said casing being provided with a port communicating with said reservoir, an air inlet port, and an exhaust port, communicative connection between said reservoir and the interior of the casing between the first-named port and said exhaust port, and means to actuate the valve to cause 90 the way thereof to be successively brought into communication with the respective ports and likewise with the aforesaid connection.

2. In apparatus of the class described, a two-part valve having a passageway extending diametrically through the valve and between the aforesaid valve parts, means for adjustably moving one of said valve parts with respect to the other part for regulating the capacity of said passageway, a casing 100 for the valve, said casing being provided with two circumferentially spaced fluid inlet ports and a discharge port, and means to actuate said valve whereby the way thereof is alternately brought into register with one 105 of said inlet ports and to make communicative connection between the other inlet port and said discharge port.

3. In apparatus of the class described, an oscillatory valve having a passageway extending diametrically therethrough, a casing for the valve, said casing being provided with two circumferentially spaced fluid inlet ports and a discharge port, means to oscillate said valve whereby the way thereof is 110 alternately brought into register with one of said inlet ports and to make communicative connection between the other inlet port and said discharge port, and adjustable devices provided on the valve-operating 115 means whereby the latter becomes inoperable to influence the valve for predetermined lengths of time when the valve passageway is brought into register with each of said inlet ports.

4. In apparatus of the class described, a casing having inlet and outlet openings, means for delivering air and liquid to the

respective inlets, and a power-actuating means provided in said casing and having a passageway extending diametrically therethrough to accommodate the liquid and 5 transfer the same into position to be expelled through said outlet opening by means of a current of air admitted through the inlet opening therefor, said means being ad-

justable to vary the capacity of said passageway with respect to the liquid.

10

Signed at Seattle, Washington, this 7th day of July, 1916.

PHILIP D. HIBNER.
